RAPID FIRE ARTILLERY GUN

William Vinnick, Whitestone, N. Y.

Application November 30, 1938, Serial No. 243,144

7 Claims. (Cl. 89—11)

My invention relates to improvements in fire arms, and the same has for its object to provide an automatic or semi-automatic rapid fire gun in which the several operations or movements of parts will be positively controlled.

Further, said invention has for its object to provide a gun in which the cartridges will be positively fed to the breech, introduced therein, and fired by a hand actuated lever.

Further, said invention has for its object to provide a gun in which one lever-actuated mechanism serves to feed the cartridge into position within the breech of the gun, and another lever-actuated mechanism serves to discharge the cartridge.

Further, said invention has for its object to provide a gun in which cam mechanism operating longitudinally of the piece is actuated by cam mechanism disposed transversely of the piece to load and discharge the same.

Other objects will in part be obvious and in part be pointed out hereinafter.

To the attainment of the aforesaid objects and ends my invention consists in the novel features of construction, and in combination, connection and arrangement of parts hereinafter more fully described and then pointed out in the claims.

In the accompanying drawings—

Figure 1 is a side elevation showing one form of gun constructed according to and embodying my said invention;

Fig. 2 is a top view thereof;

Fig. 3 is a longitudinal section on the line 3—3 of Fig. 2;

Fig. 4 is a section on the line 4—4 of Fig. 2;

Fig. 5 is a transverse section on the line 5—5 of Figure 1 showing the cartridge loading and ejecting mechanism;

Fig. 6 is a detail plan view of the magazine chute and its associated mechanism;

Fig. 7 is a front view thereof, and

Fig. 8 is a side view of the magazine chute.

In said drawings 10 designates a cylindrical member to one end of which is secured a barrel 11 which communicates at its inner end with the interior of the cylinder 10 through an opening 12 in one end thereof. The cylinder 10 is adapted to be mounted upon a suitable support or carriage, not shown.

Within the cylinder 10 is disposed a plunger 14 which is slidably supported adjacent one end by a bearing 15 secured in the cylinder 10. The plunger 14 terminates in a square inner end portion 16 having a central longitudinal bore 17

which extends entirely through said square portion 16 and said plunger 14.

18 denotes a sleeve member which is disposed upon the plunger 14 and secured at its forward end thereto by a screw 19 in order that said sleeve shall be movable longitudinally with said plunger 14. The rear end of the sleeve member 18 is provided with spiral, cam surface 20, which engages and cooperates with a reverse cam surface 21 on the right-hand end of an intermediate sleeve member 22 revolvably mounted upon the plunger 14. The sleeve 22 is provided at its left-hand end with a spiral cam surface 23 which is the reverse of the cam surface 21 at the right hand end thereof, and said cam surface 23 is adapted to engage and cooperate with a cooperating cam surface 24 on the right end of a sleeve 25 fixed at its left hand end in the end of the cylinder 10. The sleeve member 25 is disposed upon and fixed with reference to the square shaft portion 16 while the sleeve member 22 is movable longitudinally with reference to the plunger 14.

The intermediate sleeve member 22 is provided in each of its ends with a spiral groove 22^a 25 which conforms to the spiral cam surfaces 21, 23 thereof. Within said spiral grooves are received the angular ends 22^b of the fingers 22^c secured to the inner ends of the sleeve members 18, 25, whereby to restore said sleeve members 30 18, 25 to their retracted positions upon the plunger and shaft parts 14, 16, after each firing operation.

The plunger 14 is provided at its forward end with an extractor 14^a comprising hook member 35 or finger 14^b having an angular end 14^c adapted to engage with the rim of a cartridge to withdraw the same after each firing operation and deposit the same upon the hinged plate 49. The plates 48, 49 each have a portion of their rear edges 40 recessed at 48^a, 49^a in order that said plates may clear the projecting end of the extractor 14^a, when said plates are raised to eject an empty shell.

26 denotes a segmental gear fixed upon the 45 sleeve member 22.

Within the bore 17 of the plunger 14 and square shaft 16 is disposed a shaft 27 whose forward end is provided with a reduced end portion 28 50 which serves as a firing pin. The shoulder 29 in said shaft 27 is adapted to engage with a collar 30 on the forward end of the plunger 14 to limit the outward or forward movement of the shaft 27 which is held in normally retracted 55

position by a coil spring 31 disposed within the recessed end and surrounding said shaft 27.

The upper side of the cylinder 10, directly over the segmental gear 26, is cut away at 32 to accommodate a transverse sleeve member 33 which is slidably mounted in bearings 34, 34^a secured upon the opposite sides of the longitudinal cylinder 10. The sleeve member 33 is provided upon its underside with a longitudinal rack 35 in engagement with the segmental gear 26 on the sleeve member 22.

Within the sleeve member 33 is disposed a shaft 36 whose forward end is secured to the end 37^a of said sleeve member 22, and upon said shaft 36 is slidably disposed a hollow shaft 37 whose outside diameter corresponds closely to the interior diameter of the sleeve member 33. To the other end of the hollow shaft 37 is fixed a sleeve member 38 having a spiral cam surface 20 39 adapted to engage and cooperate with a cam surface 40 on the inner end of the cam sleeve member 41. The cam sleeve 41 while rotatable upon the hollow shaft 37 is held against longitudinal movement by collars 42^a, 42^b fixed on said cam sleeve 41 to each side of the bearing 34^a.

The cam sleeve 41 is provided at its outer end with a cam surface 42 which engages and cooperates with a cam surface 43 on the inner end 30 of a cam sleeve 44 fixed by a pin 44^a to the outer end of the shaft 36.

To actuate the cam sleeve 41 the same is provided with an operating lever 45 whereby the same may be rotated.

35 The forward upper side of the cylinder 10 is provided with a feed opening 46 in which is secured a hinged cover 47 having a handle 47^a upon its under side with a curved plate 48, whose inner end is extended upwardly and engages with the under side of hinged plate 49 pivotally secured to the inner side of the cylinder 10. The said plate 49 is normally supported upon the upwardly bent end of the curved plate 48, and is adapted to raise the said plate 49, when the cover 45 47 is raised, to eject the empty shell and to receive a loaded shell when and as the cover 47 is being opened and closed.

Communicating with the feed opening 46 is a magazine chute 50 secured to the cylinder 10, by 50 which the cartridges 50^a are fed one at a time to the plate 49 from which the same are then introduced into breech 52 by the plunger 14. The feed of the cartridges 50^a to the plate 49 is controlled by an escapement comprising a curved 55 plate 50^b whose longitudinal edges extend through transverse slots 50^c in the floor of the chute 50. The said curved plate is mounted upon a bar 50^d which has its opposite end secured to the lower ends of the arms 50^e, 50^f, pivotally secured at 50^e 60 to the side walls 50^h of the chute. The bar 50^d is provided intermediate its ends with a depending operating arm 50^m to actuate the curved plate 50^b to release the cartridges one at a time as the arm 50^m is partially rotated by the engagement 65 of the empty shells in being ejected from the cylinder 10 of the gun. The arm 50^e is provided with an extension 50ⁿ to the free end of which is attached one end of a spring 50^p having its other end secured to a projection 50° on the side walls 50^h of the chute. The spring 50^p serves to hold the curved plate 50^b in its position to retain a cartridge, and to return said plate to its normal position after releasing a cartridge.

70 Stops 50^q are provided on the opposite side 75 walls of the chute 50 to engage with the arms

50^e to limit the forward movement thereof after each actuation of the operating arm 50^m.

At the rear end of the cylinder is secured a bracket 53 having depending lugs 54, 55, and on said bracket is pivotally mounted a spring 5 actuated detent or trigger 56 having its lower end extending through a slot in the lug 55, and whose upper end 57 is normally maintained in elevated position by a spring 58 having one end secured to the detent 56, and its other end to the lug 54.

To the rear end of the shaft 27 is secured a slide 59 having its free end bifurcated longitudinally to admit the upper end of the detent 56, and at the end of said bifurcation are upwardly 15 extending posts 61 upon which is disposed a vertically-movable slide 62. The slide 62 has a cam face 63 at its inner side adapted to engage with the upper end of the detent 56, when the shaft 27 is in retracted position, and ready to 20 be released to project the firing pin 28 at its forward end into engagement with the cartridge.

To operate the gun the arm 50^m of the magazine chute 50 is actuated to release a cartridge and permit the same to be fed to the plate 48 25 into position to be rammed into the breech opening 52. Hereupon the lever 45 is actuated and the cam sleeve 41 rotated and in so doing cause the cam surfaces at the opposite ends thereof to engage with the contiguous cam surfaces of 30 the cam sleeves 42 and 40, and thereby cause the rack 35 on the under side of the cam sleeve 22 to rotate the gear 26 on the cam sleeve 22 within the cylinder 29, and rotate the cam sleeve 22 thereby causing the cam surfaces 21 and 23 35 at its opposite ends to coat with the cam surfaces 20 and 24 of the cam sleeves 18 and 25 and move the latter longitudinally in opposite directions upon the shaft parts 16, 17, and cause the cam sleeve 18 which is fixed to the plunger 14 40 to move to the right and ram the cartridge home in the breech opening 52, and as the movement of the cam sleeves 18, 22 and 25 is continued the shaft 27, in moving outwardly towards the rear, will release the slide 62 and permit the firing 45 pin 28 to be projected against the primer of the cartridge, and fire the same.

To reload the piece after it has been fired, the lever 45 is thrown forwardly, the cam sleeve 42 partially rotated and the cam sleeves 38 and 22 50 actuated and the rack 35 moved and cause the same to rotate the gear 26 on the sleeve member 22 and rotate the said sleeve member 22, and in so doing cause the spiral grooves 22^a at the ends thereof which engage with the spiral fingers 22^c 55 on the cam sleeve members 18 and 25 to move inwardly towards the ends of said intermediate sleeve member 22 and carry the plunger 14, which is fixed to the cam sleeve member 18, rearwardly, and cause the extractor 14^a at the forward end thereof to withdraw the empty shell from the breech opening 52, and deposit the same upon the curved plate 49 actuated by the plate 48 attached to the hinged cover 47, to eject the empty shell, and in so doing cause the empty shell to strike the arm 50^m of the feed escapement and move the same rearwardly thereby releasing the foremost loaded shell in the magazine chute 50, and cause the loaded shell to drop into position upon the recessed portion of the plate 49, ready to be 60 rammed into the breech 52 upon the next projecting of the plunger 14.

As the cam sleeve members 18 and 25 are retracted towards the intermediate cam sleeve member 22, the shaft part 16, and shaft 27 will 70 75

be moved rearwardly, and cause the slide 59 carrying the vertically-movable slide 62 to ride over the nose 57 of the spring-actuated detent 56, and hold the slide 59, shaft 27, and the reduced end thereof forming the firing pin 28 to be held to retracted or "ready" position to be released upon actuation of the trigger 56.

The above loading and firing operations are thereupon repeated.

Having thus described my said invention what I claim and desire to secure by Letters Patent is:

1. A rapid fire artillery gun comprising a cylindrical casing, a barrel extending from and communicating therewith, a shaft supported longitudinally in said casing, a series of cooperating cam sleeves mounted on said shaft for reciprocating the same, a second shaft at right angles to said first-named shaft, a series of cam sleeves mounted on said second shaft, means operatively connecting certain of said second-named cam sleeves with certain of said first-named cam sleeves for actuating said first-named cam sleeves to project and retract said first-named shaft, means for feeding loaded shells to said barrel, and means for ejecting the empty shell from said casing.

2. A rapid fire artillery gun comprising a cylindrical casing, a barrel extending from and communicating therewith, a shaft supported longitudinally in said casing, a series of cooperating cam sleeves mounted on said shaft for reciprocating the same, a second shaft at right angles to said first-named shaft, a series of cam sleeves mounted on said second shaft, means operatively connecting certain of said second-named cam sleeve with certain of said first-named cam sleeves for actuating said first-named cam sleeves to project and retract said first-named shaft, means for feeding loaded shells to said barrel, means for ejecting the empty shell from said casing, means for feeding loaded shells to said casing, said means being actuated by engagement with said empty shells as the latter are ejected from said casing.

3. A rapid fire artillery gun comprising a casing, a barrel communicating therewith, a shaft in said casing, cam means on said shaft for reciprocating said shaft, a second shaft supported adjacent said first-named shaft, cam means on said shaft, means operatively associated with said last-named cam means for actuating said first named cam means to project said first-named shaft into engagement with a shell in said barrel, means for feeding cartridges to said casing and for ejecting the empty shells therefrom, and a chute for loaded shells, means associated with said chute for feeding the shells singly to said casing, and a member operated by the empty shells as the same are ejected from the casing for actuating said feeding mechanism.

4. A rapid fire artillery gun comprising a casing, a barrel communicating therewith, a shaft in said casing, cam means on said shaft for reciprocating said shaft, a second shaft supported adjacent said first-named shaft, cam means on said shaft, means operatively associated with said last-named cam means for actuating said first named cam means to project said first-named shaft into engagement with a shell in said barrel, and means for feeding

cartridges to said casing and for ejecting the empty shells therefrom, said means including a hinged cover for closing an opening in said casing, an operating handle therefor, a hinged member secured within said casing for supporting a loaded cartridge in position thereon to be rammed by said first-named shaft, and means secured to said cover and engaging said hinged member adjacent its free end for actuating the same to eject the empty shells.

5. A rapid fire artillery gun comprising a cylindrical casing, a barrel extending from and communicating therewith, a shaft supported longitudinally in said casing, a series of sleeve members mounted on said shaft having cooperating cam surfaces for reciprocating the same, a second shaft supported at right angles to said first-named shaft, a series of sleeve members mounted on said second shaft having cooperating cam surfaces, means operatively connecting certain of said second-named sleeve members with certain of said first-named sleeve members for actuating said first-named sleeve member to project and retract said first-named shaft, means for feeding loaded shells to said barrel, means for ejecting the empty shell from said casing, and means for feeding loaded shells actuated by the discharge of said empty shells as the latter issue from said casing.

6. A rapid fire artillery gun comprising a cylindrical casing, a barrel extending from and communicating therewith, a shaft supported longitudinally in said casing, a series of sleeve members mounted on said shaft having cooperating cam surfaces for reciprocating the same, bearing on said casing, a second shaft supported in said bearings at right angles to said first-named shaft, a series of sleeve members mounted on said second shaft having cooperating cam surfaces, means operatively connecting certain of said second-named sleeve members with certain of said first-named sleeve members for actuating said first-named sleeve member to project and retract said first-named shaft, means for feeding loaded shells to said casing, and means for ejecting the empty shell from said casing, and means for feeding loaded shells actuated by the discharge of said empty shells as the latter issue from said casing.

7. A rapid fire artillery gun comprising a cylindrical casing, a barrel extending from one end thereof and communicating therewith, a shaft supported longitudinally in said casing, a series of sleeve members mounted on said shaft having cooperating cam surfaces and a gear on one of said sleeve members for reciprocating the same, bearings on said casing, a series of sleeve members mounted on said second shaft having cooperating cam surfaces, a shaft disposed within said last-named sleeve members, a rack on one of said second-named sleeve members in engagement with the gear on one of said first-named sleeve members, for actuating said first-named cam sleeve members to project and retract said first-named shaft, means for feeding loaded shells to said barrel, and means for ejecting the empty shell from said casing, said ejecting means serving to project empty shells into engagement with said feeding mechanism to feed the loaded shells to said casing.

WILLIAM VINNICK.
